[57] CLAIM

The ornamental design for an element for a shoe, as shown and described.

DESCRIPTION

FIG. 1 is a perspective view of an element for a shoe showing my new design;

FIG. 2 is a side elevational view thereof;

FIG. 3 is a top view thereof;

FIG. 4 is a front view thereof; and,

FIG. 5 is a rear view thereof.

The broken line showing of the enclosed regions within the element is for illustrative purposes only and forms no part of the claimed design.
